UNITED STATES PATENT OFFICE.

JOHN BROMET, FRANK THORMAN, AND HENRY CLAYTON WOOD, OF TADCASTER,
ENGLAND.

CENTRIFUGAL APPARATUS FOR TREATING SEWAGE.

1,098,554.

Specification of Letters Patent.

Patented June 2, 1914.

Application filed May 19, 1913. Serial No. 768,591.

To all whom it may concern:

Be it known that we, JOHN BROMET, FRANK THORMAN, and HENRY CLAYTON Wood, subjects of the King of Great Britain and Ireland, residing at Tadcaster, in the county of York, England, have invented new and useful Improvements in Centrifugal Apparatus for Treating Sewage, of which the following is a specification.

10 This invention relates to an improved process and apparatus for the treatment of sewage, trade effluent, foul wastes, and other mixtures of solids and liquids.

The object of our invention is to separate 15 by a continuous process the suspended solid matter from the liquid in sewage and other mixtures of solids and liquids, and to avoid the contamination of the effluent by the untreated mixture. For this purpose we dis- 20 charge the mixture of solids and liquids directly into the apparatus hereinafter described. The said apparatus may be used either single or, by placing several in series, as may be required according to the volume 25 of material to be dealt with. In the case of sewage, the contents of the sewer, on entering the sewage disposal works and after being passed through a rough screen, are mixed (if necessary) with a suitable pre- 30 cipitant, and are at once passed through the apparatus. In the case of trade waste, from works and factories and the like, dealt with by manufacturers themselves, the waste is rough screened and precipitant added (if 35 necessary) as soon as possible after the waste has left the factory.

Figure 1 is a front elevation (partly in section) showing the general arrangement of our improved centrifugal apparatus as 40 arranged in series. Fig. 2 is a plan of Fig. 1, also partly in section. Fig. 3 is a side elevation (partly in section) of Fig. 1. Fig. 4 is a sectional elevation on an enlarged scale showing details of construction of 45 centrifugal apparatus. Fig. 5 is a sectional plan of Fig. 4.

Similar references are employed to indicate corresponding parts throughout the several views.

50 According to our said invention we provide revolving cylindrical apparatus consisting primarily of three concentric pans. The outer pan A is formed with vertical sides, flat bottom B, and flat top C with 55 central funnel head D, the pan A being ro-

tated by an axial shaft E having driven pulley F and roller-bearing footstep G, to which shaft the pan A is rigidly secured at the bottom by means of a keyed boss H. In the bottom of the outer pan A, toward its 60 outer periphery, are sludge and drainage valves I controlled from a hand wheel J by a lever K, sliding block L, and link motions M attached to the under-side of the valves. The intermediate pan N is separate 65 from and slightly less in diameter than the outer pan A and is formed with vertical sides fitting inside the outer pan, and is rotated by a loose sleeve O fitted over the central shaft E and driven by gear wheels 70 P Q from the counter shaft R having suitable disconnecting gear. The sleeve O and intermediate pan N are connected at the bottom by a keyed boss S having a series of radial arms T, the said intermediate pan 75 N being quite open at the bottom. The joint at the bottom and top of the intermediate pan N is formed with brass strips and leather or other material suitable for protecting the pans from binding. The inner 80 pan U is of considerably reduced diameter and is fitted within the outer and intermediate pans. It is formed with vertical sides, flat top V, short loose boss W at the top within which the driven sleeve O of the intermediate pan N is free to revolve, and radial strengthening arms X at the open bottom attached to a central annular ring Y fitting loosely around the said driven sleeve O. The tops of the inner and outer 85 pans U and A are connected rigidly together by means of a series of pipes Z each having an external delivery pipe 1 extending radially outward toward an annular trough or channel 2 surrounding the apparatus and communicating with an effluent channel 3 leading to suitable filters or irrigation land. Attached to the outer side of the inner pan U are upright scrapers 4 having strengthening stays 5, these scrapers 100 projecting across the annular space between the intermediate pan N and the inner pan U, and being so fitted as to allow the collected sludge or solid matter to be freely emptied through the aforesaid sludge valves I in the bottom of the outer pan A.

The *modus operandi* is as follows:—The sewage or other foul wastes or combinations of solids and water to be dealt with is fed continuously into the machine, by way 110

of the sewage channel 6 and feed trough 7 through the funnel head D of the outer pan A, and passes down the space between the tops of the outer and inner pans. The sewage being thus fed direct to the periphery of the apparatus, where the greatest pressure exists, the solid matter at once separates from the liquids and adheres by the centrifugal pressure to the sides of the collecting 10 or intermediate pan N. The travel of the incoming sewage continues in a downward direction due to head of feed toward the open bottom of the inner pan U, and during the whole of such travel the solids in suspension are being continuously extracted and collected on the sides of the intermediate pan N. The depth, diameter, and speed of revolution of the pans may be varied according to the volume to be treated and the density of 20 the suspended materials or consistency of the mixture. The ordinary principles governing the construction of centrifugals will provide particulars enabling these variations to be made.

25 The apparatus is designed so that the material to be dealt with has to travel the full depth of the periphery of the apparatus before being discharged. When the bottom of the pan is reached the water is clarified, and 30 this clarified water passes under the open bottom of the inner pan U and flows in an upward direction toward the center of the apparatus.

35 The apparatus provides not only for separating the solids from the liquids but also for providing a compartment for the clarified liquid column which cannot be contaminated by readmixture with the incoming foul solids and liquids. This compartment

40 being preferably tapped at the top in the case of low heads, but it may be tapped at the bottom anywhere under the inner cone or pan U. The space inside the inner pan U may be termed the clarified liquid column.

45 The clarified water is, by combination of the pressure of centrifugal action and of the head of the feed, continuously extracted through the aforesaid connecting pipes Z and external delivery pipes 1, the incoming 50 sewage or foul water being by this means prevented from coming into contact with the clarified liquid. If the effluent is not clear the speed of the apparatus may be increased.

55 Before removing the solids collected and concentrated to a semi-dry condition on the intermediate pan N, the doors of valve I are slightly opened and the water contained in the apparatus is drawn off (while the machine is in motion or otherwise) through the valves I, and is discharged through the drain 60 8. The collected solids are removed either by stopping the machine, fixing stationary

the outer pan A (to which is attached the inner pan U with scrapers) with suitable 65 brake attachments such as are used in hydro-extractor work, and independently revolving the intermediate pan N with sludge attached, or (vice versa) by fixing stationary the intermediate pan N and revolving the outer and 70 inner pans, the collected solids in either case being detached by the scrapers 4 and emptied through the valves 1, for removal by means of hoppers 9, band conveyers 10, and elevator 11. 75

For the purpose of collecting and discharging the sludge the following alternative method may, if preferred, be adopted, that is to say:—the independently driven pan N may be dispensed with, the sludge 80 deposited on to the periphery of the outer pan A; suitably stayed independently driven rotary scrapers attached to the loose sleeve O being in such case substituted for the fixed scrapers 4 previously described. The nature 85 of our invention is the same in both these methods, the only difference between the two being that in the former it is the collecting surface and in the latter the scrapers that are independently driven. In the case 90 of small installations the apparatus may be provided with a suitable metal casing or other arrangements and modifications, the principle of the machine being maintained as to dividing the solids from the liquids. 95

We wish it to be understood that we do not claim generally or irrespective of our improvements as herein set forth the use of a centrifugal machine for the purposes of the separation of mixtures of solids and 100 liquids and for dessication; but

We claim:

The improved centrifugal apparatus for the treatment of sewage and the like, comprising an outer revolving pan, a central 105 inlet head therein, a smaller inner concentric pan connected to and revolving with said outer pan, an independently driven intermediate pan forming a collecting surface for the solids separated during the passage 110 of the sewage from said inlet head toward said inner pan, scrapers and valves for removing and discharging the collected and concentrated solids, and inclined connecting pipes and external radial delivery pipes for 115 continuously discharging the clarified water from said inner pan without any possibility of contamination by contact with the incoming sewage, substantially as herein set forth.

JOHN BROMET.

FRANK THORMAN.

HENRY CLAYTON WOOD.
